UNITED STATES PATENT OFFICE

GERALD F. CAVANAGH, OF CLEVELAND, OHIO, ASSIGNOR TO THE OHIO RUBBER COMPANY, OF CLEVELAND, OHIO, A CORPORATION OF OHIO

RUNNING BOARD

Application filed August 30, 1930. Serial No. 478,968.

This invention relates to running boards for vehicles and the like, and more particularly to an improved form of running board of composite steel and rubber construction.

5 It is an object of the present invention to provide an improved marginal finish, cover, or binding construction for devices of this character.

Another object is to provide improved 10 means for securing the cover strip in position on the running board after the rubber covering thereof has been applied by molding and vulcanization to the running board body.

15 Further objects of the invention are to simplify and improve the construction, assembly, appearance and durability of devices of this character, and to render the same economical in manufacture.

20 Other objects and features of novelty will be apparent as the following description proceeds, reference being had to the accompanying drawings, in which the preferred embodiment of the invention is illustrated in 25 connection with the type of steel and rubber construction disclosed and claimed in the copending application of Budd Bronson, Serial No. 241,771, filed December 22, 1927, for a composite steel and rubber article.

30 However, the present invention is not limited thereto, as it is adapted to other composite steel and rubber constructions.

In these drawings:

35 Figure 1 is a top plan view of a running board constructed according to my invention, a part of the rubber covering being shown broken away to reveal the metal body;

Fig. 2 is a side elevation of the structure shown in Fig. 1;

40 Fig. 3 is an enlarged sectional elevation taken along the line 3—3 of Fig. 1;

Fig. 4 is an end elevation of the structure shown in Fig. 1;

Fig. 5 is a detail section taken along the 45 line 5—5 of Fig. 1; and

Fig. 6 is a detail sectional view on an enlarged scale, showing the binding strip secured to the front flange of the running board.

50 Referring more particularly to the draw-

ings, the running board body is designated 10, this body being formed from sheet metal by stamping the same into the shape illustrated. In forming this member I prefer to use that type of sheet metal which is known commercially as hot-passed steel because this material has an inherent surface roughness or porosity by virtue of which a desired uniform and permanent adherence between the rubber and steel is obtained by some of the rubber of the covering being squeezed into the interstices of the metal during the vulcanizing operation. The body 10 is generally rectangular in shape, and the greater central portion thereof is depressed as at 11, 60 which depression is adapted to receive the rubber covering. In forming this depression, the margins remain as upstanding beads, there being a rear bead 12, and end beads 13 and 14. The outer edges of these beads are 65 extended downwardly, thus forming a depending rear flange 15, and depending end flanges 16 and 17.

At the front edge of the running board body 10, or in other words, along the edge thereof which is most remote from the longitudinal center-line of the vehicle, there is formed a down-turned flange 18 which, in the form shown, is curved along a fairly large radius, so that the flange is in the nature of a smooth 70 roll. The end beads 13 and 14 are carried down along the ends of this roll so that the depression 11 in the body extends down over the flange 18.

The body as described is covered with a 75 non-metallic cover, preferably sheet rubber such as that indicated at 19, but it is to be understood that any suitable non-metallic material may be used for this purpose. This cover fills the depression 11 and extends down 80 over the flange 18. The body 10 is preferably provided with a plurality of substantially uniformly spaced holes 20, distributed over the area thereof, and in the molding and vulcanizing operation some of the covering 85 material will extend through the holes 20 and thus form rubber rivets 21 which assist in securing the covering to the metal body. The vulcanization of the rubber to the inherently 90 rough surface of the hot-passed steel will give 95 100

a very secure bond between the rubber and steel, which when reinforced by the rubber rivets 21 will insure the permanent attachment of the rubber covering 19.

5 In forming the running board body it will be noted that along the lower edge of the downwardly extending flange 18, the metal of the body is reversely bent, or in other words is bent upwardly with respect to the 10 lower edge of the flange 18, as is clearly shown in Figs. 2 and 6, to form the longitudinally extending, upstanding bead or shoulder 22. This bead is preferably made rounded in form to correspond with the rounded beads 12, 13 15 and 14 and extends between the beads 13 and 14 so that the beads 12, 13, 14 and 22 together form a substantially continuous upstanding bead around the metal body. It should be noted particularly that the bead 22 is spaced 20 from the flange 18 to provide the longitudinally extending groove 23 therebetween, into which the edge of the rubber covering 19 extends. This groove thus provides a secure 25 anchorage and protection for the edge of the covering which prevents the covering from being torn loose.

Along the outer edge of the bead 22 the metal is extended downwardly to form the longitudinally extended marginal flange 24 30 which depends below the bead 22 and also below the lower edge of the flange 18. At its lower edge the flange 24 terminates in a marginal lip or flange 25 which extends laterally beneath the bead 22, or in other words, extends 35 inwardly toward the vehicle.

The rubber covering of the metal body does not extend over the flange 24 and in running boards of this type having an exposed portion along the front edge thereof, it has been 40 customary to coat this surface with lacquer or other finishing material. However, such coatings of lacquer or other material quickly become chipped and scratched upon being kicked by persons entering the vehicle, and 45 not only mars the appearance of the finish but exposes the metal body to corrosion. To provide the flange 24 and the bead 22 with a covering which will not readily become scratched or marred, and which will give the running 50 board a decorative and finished appearance, I employ the binding strip or sheath 26. This binding strip is preferably constructed of material which can be easily polished and which does not readily become scratched, corroded or discolored, such as stainless steel 55 coated with nickel, chromium or the like.

The binding strip 26 is applied to the metal body after the rubber covering 19 has been secured thereto by the molding and vulcanizing operation. To enable the binding strip to snugly fit the bead 22 and to be permanently secured in place I construct the same so that the upper portion thereof has a longitudinally extending curved flange 27 which is hook-like 60 in cross-sectional shape, as clearly shown in

Fig. 6, and which has substantially the same radius of curvature as the bead 22. When the binding strip is applied to the metal base to which the rubber covering has been previously secured, the curved flange 27 is hooked 70 over the bead 22 so that the free edge of this flange extends partway into the groove 23 and presses against, or into, that portion of the rubber covering which extends into the groove. By extending the edge of the rubber 75 covering, and of the binding strip, into the groove 23, it will be readily seen that these edges are not only concealed, but they are protected against being torn loose from the metal body.

After the curved flange 27 of the binding strip has been hooked over the bead 22, the strip is pressed flat against the surface of the flange 24 and is bent around the laterally extending lip 25 thereby forming the longitudinally extending hook-like clamping flange 28 which secures the lower edge of the binding strip in place.

In order that the upstanding beads 12, 13 and 14 may also have a decorative and finished appearance, and may harmonize with the bead 22 extending along the front edge of the running board, these beads are provided, respectively with binding strips 29, 30 and 31. These binding strips, which are applied to the metal body after the rubber covering has been secured thereto, are each formed with a curved or hook-like longitudinally extending flange 32 which snugly fits its respective bead so that the free edge of this flange extends 95 partway into the depression 11 of the metal body and presses into, or against, the rubber covering secured in the depression. From the curved flange 32 the binding strips 29, 30 and 31 are extended down upon the flanges 15, 16 105 and 17, respectively, so that the lower edges of the strips will be concealed by being clamped between these flanges and those portions of the vehicle structure with which these flanges cooperate. For permanently securing 110 the binding strips in place, the portions thereof which extend downwardly upon the flanges 15, 16 and 17 are sheared at spaced points to provide the lugs or tongues 33 which extend through correspondingly spaced openings 34 formed through the flanges. These tongues, as clearly shown in Fig. 5, are bent 115 toward the curved flange 32 and around the edges of their openings so as to form retaining hooks which cooperate with the curved flanges in retaining the binding strips in 120 place.

It will now be readily seen that in the composite running board construction which I have devised, the binding strips not only give 125 the article a decorative and finished appearance, but protect marginal portions of the metal body from wear and corrosion, particularly the exposed front edge thereof. Furthermore, it will now be understood that the 130

longitudinally extending groove along the front of the metal body provides an anchorage for the edge of the rubber covering and for the edge of the binding strips, and also 5 effectively conceals and protects the edge of these members.

While the preferred embodiment of the present invention has been illustrated and described in such detail as to enable anyone 10 skilled in the art to practice the invention, nevertheless it will be understood that the invention is not limited to the details disclosed other than as necessitated by the development of the prior art; but instead it will be understood 15 that the invention embraces such embodiments of the broad idea as fall within the scope of the appended claims, it being obvious that various changes may be made with respect to the disclosed embodiment 20 without departing from the spirit of the invention.

Having thus described my invention, I claim:

1. A running board comprising a metal 25 body having a depending flange along one edge thereof, said flange having an integral reversely bent portion providing a longitudinally extending groove, and non-metallic covering secured to said body with one edge 30 thereof extending into said groove.

2. A running board comprising a metal body having a depending flange along the front edge thereof and a shallow depression in its upper surface extending down into said 35 depending flange, said flange having an integral reversely bent portion providing a longitudinal groove in communication with said depression, and non-metallic covering secured in said depression with one edge thereof 40 of extending into said groove.

3. A running board comprising a metal body having a depending flange along the front edge thereof the lower portion of said flange being extended outwardly beyond its 45 upper portion to provide a bead-like longitudinal shoulder, rubber covering secured to said metal body with one edge thereof extending along said shoulder, and a binding strip covering the lower portion of said flange 50 and having the upper edge thereof hooked over said shoulder and engaging the previously applied rubber covering.

4. A running board comprising a metal body having a depending flange along the front edge thereof the lower portion of said flange being extended outwardly beyond its upper portion, said flange being reversely 55 bent at the junction of said upper and lower portions to provide a longitudinal bead-like shoulder and a longitudinal groove, rubber covering secured to said metal body with one edge thereof extending into said groove, and a binding strip covering the lower portion of 60 said flange and having the upper edge thereof 65

of hooked over said shoulder and extended into said groove.

In testimony whereof, I hereunto affix my signature.
